UNITED STATES PATENT OFFICE.

WALTER N. VANCE, OF CHICAGO HEIGHTS, ILLINOIS, ASSIGNOR TO DURAND STEEL
LOCKER COMPANY, OF CHICAGO, ILLINOIS, A CORPORATION OF ILLINOIS.

SHELF AND RACK DOOR.

Application filed October 11, 1924. Serial No. 742,962.

This invention relates in general to shelving, racks, lockers and the like, and has more particular reference to the provision of door closures for shelves, racks, and the like.

A principal object of the invention is the provision of door closures for shelves and the like which may be readily positioned on shelving already erected and not designed particularly to receive such door closures, and this without reforming the shelving parts or the provision of complicated, cumbersome or unsightly attaching or other auxiliary members.

Shelving, and particularly metal shelving, is usually provided so that the shelves may be adjusted vertically at different distances one above the other, being on this account adjustably supported from frame uprights or partitions. My present invention from certain aspects contemplates the use of the shelf receiving portions of said uprights to facilitate attachment of the door, and the invention has for a further and highly important object the provision of door closures which may interlock with the front-to-back sides of the uprights and preferably in the openings or other agencies provided in the uprights for holding the shelves, and this while at the same time permitting unrestricted adjustment of the shelves in the space closed by said door closures.

The invention has for a further object the provision of doors which may be provided for the locker after the shelves are erected and without requiring even temporary removal of the shelves or the unloading of them as an incident to the attachment of the doors.

A still further object of the invention is the provision of a door closure for shelving and the like having hinged connections adjustable lengthwise of the space to be closed by the doors and lengthwise also of the doors themselves.

Another important object of the invention is the provision of means for locking one or more doors to readily adjustable shelves, and this without limiting the range and freedom of adjustment of said shelves.

Another object of the invention is the provision of a door closure and a hinge connection to shelving to which the door is at

tached, which will by reason of its construction and the manner of attaching it to the frame permit of the use of relatively light material to attain the necessary and desired strength, rigidity and durability.

A still further object of the invention is the provision of a shelf closure which may be provided to extend merely over a part of the shelf assemblage without marring the appearance of the whole assemblage and which may be shifted to other parts of the assembly or added to by the addition of other closures.

Numerous other objects and advantages of the invention will be apparent as it is better understood from the following description, which taken in connection with the accompanying drawings discloses a preferred embodiment thereof.

Referring to the drawing.

Fig. 1 is a front elevation of a portion of a section of the shelves provided with a door closure embodying my present invention;

Fig. 2 is a section taken substantially on the line 2—2 of Fig. 1;

Fig. 3 is a section taken substantially on the line 3—3 of Fig. 2;

Fig. 4 is a diagrammatic view of a blank cut to appropriate form to form a hinge connection;

Fig. 5 is a perspective view of a hinge connection formed from the blank shown in Fig. 4;

Figs. 6 and 7 are side views of one of the fastening bolts used to retain the hinge in closed position;

Fig. 8 is a view taken substantially on the line 8—8 of Fig. 1;

Fig. 9 is a section taken substantially on the line 9—9 of Fig. 8;

Fig. 10 is a perspective view of the latch member adapted for attachment to one of the vertically adjustable shelves; and

Fig. 11 is a partial perspective detail of the companion latch bar carried by the door itself.

For the purpose of illustrating the invention I have shown on the drawing a portion of metal shelving comprising tubular uprights 21 connected by front-to-back partitions 22 and also by front and back bearings or cross-supports 23. The uprights 21 are

provided in their front-to-back sides with regularly spaced slots 24, each of which in the present instance is composed of a lower smaller tapered part 25 and an upper slightly larger tapered part 26 and a top enlarged opening 27. The cross-supports 23 correspond in number with the number of shelves employed. The ends of the cross-supports are located or wedged tightly in the lower slot parts 25 of the appropriate slots and upon them rest the edges of the shelves 28. The shelves 28 have parts engaged at or near the bottom of the intermediate slot parts 26. Beyond the bearers the shelves are preferably bent down at 29 and back upon themselves again at 31 to provide edges 32 disposed closely adjacent the bottom of the bearers 23. These shelves are adjustable and arrangeable at irregular intervals between the uprights by moving the cross-supports and the shelves to produce engagement with desired or appropriately located slots 24. So much of the shelving shown on the drawing as has just been described is well known in the art to which this invention relates being disclosed in numerous earlier patents to me, and made in the form shown on the drawing by my assignee, Durand Steel Locker Company. More particular description of it is not therefore thought to be necessary.

The shelf section shown on the drawing is adapted to be provided with a door closure comprising doors 33 and 34 hinged to adjacent uprights and overlapping at the center to close the space therebetween and throughout any given or desired portion vertically of the shelf assemblage. The hinged sides of the two doors 33 and 34 are identical in the present instance and a description of the hinge arrangement of one door will apply to the other.

Each door is of sheet metal and at its hinged side is bent back at right angles at 35 to provide an inwardly extending part 36 and therebehind is bent to substantially semi-circular form as indicated at 37, the semi-circular portion 37 forming with the body of the front wall a recess or internal bearing for the hinged connection. The extreme edge 38 is spaced back from the front wall an appreciable distance for a purpose to be presently described.

Corresponding to the distances between the slots the material of the curved portion 37 of the door is cut away as indicated at 39, the arrangement being such that these cut away parts may be disposed accurately opposite or adjacent the intermediate slot parts 26 of the slots 24 when the door is in proper position. The hinge member is shown in Fig. 5 and consists of a single sheet of metal bent to provide an elongated cylindrical part 41 from which an arm 42 extends and this arm is reinforced by flanges 43 at its sides.

The edges of the flanges 43 are cut away at 44 to accurately fit the side faces of the tubular uprights 21 and a bolt receiving opening 45 is located in position to come opposite the vertical center of the slot 24.

The blank from which this hinge member is constructed is shown diagrammatically in Fig. 4. From this figure it will be noted that the blank is of T form, the head 46 of the T being the part forming the cylindrical portion 41 of the hinge member, and the tail 47 thereof forming the arm 42. The flanges 43, of course, are extensions of the side of the body of the arm and are cut at 48 at their ends from the part 46 and bent up on lines of bend 49 to bring them to the desired parallel relation shown in Fig. 5. The outer edge of the head 46 of the blank is slotted at 51 to permit this edge of the blank to be bent around and embrace the adjacent ends of the flanges 43 in the slots. The diameter of the cylindrical part 41 is such that it fits neatly within the recess formed between the curved part 37 and the body of the door. The flanges 43 are of such width that they may be arranged between the edge 38 of the bend of the door and the body and slid lengthwise therebetween to adjust the hinge connection vertically into desired relation with any of the slots 24. This sliding movement, however, can only occur when the hinged member is laid back against the door as indicated in dotted lines in Fig. 3. This relation can not be assumed when the hinged members are secured to the uprights for the reason that at such times the door is unable to assume the substantial parallelism with the hinge arms shown by reason of the shelves and cross bearers being in the way as will be readily understood.

Each hinged member is fastened to an upright by a bolt 52 having an oblong head 53. This head may be inserted through the intermediate part of the slot and thereafter turned to dispose the longer axis horizontally as is indicated in Fig. 2. The bolt thus arranged extends through the opening 45 and receives a nut 54 to fasten the hinge member tightly in place. In the form of the invention shown on the drawing the hinge member may thus be secured to any of the slots whether the particular slot engaged by the hinge member be actually supporting shelves or not. The hinge members may thus be positioned in any convenient slots without disturbing the vertical adjustment of the shelves or requiring any particular formation of the tubular uprights.

It will, of course, be understood that it is not necessary to the invention from several aspects that the arrangement be such as to permit a shelf and hinge connection to be engaged in the same slot at the same time. The two doors are provided with inwardly extending flanges 55 and 56 at their adjacent

ends and the one is caused to overlie the other in the present instance by securing an angle iron 57 to one of the door flanges 55, the flange 58 of the angle iron being arranged 5 to overlie the body of the other door.

A latch keeper is provided for latching or locking the doors in closed relation and as shown on the drawing is attached to a carrier and to one or more of the shelves. 10 A metal strap of desired width is bent at 59 and 61 to provide an upper horizontal part 62 and an intermediate downward and forwardly inclined part 63 and a lower horizontal operative portion 64. The parts 62 15 and 64 are provided with perforations 65 and 66 to receive fastening bolts from the shelf. This latching member is secured in place as may be seen by viewing Figs. 8 and 9 and with the upper horizontal part 62 20 resting against the underface of the shelf 28 and the lower horizontal part 64 resting against the underfaces of the cross bearer 23 and shelf edge 32, bolts 67 and 68 extending through the shelf and through the openings 65 and 66 of the latch member. The 25 openings in the shelf through which these bolts extend may be openings provided for other purposes as for example the reception of fastening devices for shelf dividers and 30 shelf partitions or they may not as conditions may render expedient.

A latching or locking element or member formed preferably of a bar 71, having key-hole slots 72, is positioned behind the outer 35 overlapping door and against its flange 55. This latching bar is held slidably in position by pins or headed rivets 73 which may enter the large portion of the keyhole slots and have sliding engagement in the smaller. 40 A number of lips 74 are struck up and extend out from the latch bar in position to engage upon and behind a hooked arm 75 forming a continuation of the part 64 of the latch, this arm terminating in bent up portion 76 45 forming the hook. A struck up lip 74 is provided adjacent each possible shelf position when the shelves are carried in the slots so that the latch bar may be engaged by a latch keeper supported in any of the 50 supporting slots. A portion 77 of the latch forms a door stop and engages the inner edge of the flange 56 of the inner door thus preventing the edges of the shelves from coming in contact with the door flanges and 55 preventing marring of the shelves through the presence of the doors. The latch bar is adapted to be raised and lowered in manipulating the door by the handle 78 disposed outside and having a pair of inwardly extending lips 79 disposed through slots in 60 the door and secured by bolts or screws 81 with the latch bar.

It will be manifest that both the hinge action and the locking action of the door 65 readily permit of full freedom of shelf ad-

justment and that the parts may all be assembled in the shelving without requiring removal of any of the shelves or even their unloading. The hinge connection is such that the forces sustained by it fall along the 70 plane of the arms of the hinge members and transversely of the bolts 52 so that there is little likelihood of damage to any of the parts and they may therefore be safely made 75 of relatively light material.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely 80 a preferred embodiment thereof.

I claim:

1. Metal shelving, comprising spaced uprights having a vertical series of spaced slots adapted to furnish detachable engagement, a support for shelves to provide a 90 tier of vertically adjustable shelves supported between said uprights, shelf members engaging portions of said slots, a door having hinged engaging portions spaced thereon to correspond with the spacing of 95 said shelf supporting slots, hinge members for said doors, said hinge members being secured to said uprights by means of connections engaging portions of said shelf supporting slots not occupied by said sup- 100 ported shelves, a latch keeper carried by a shelf of said tier, a latching bar shiftably mounted on said door, said latching bar having a vertical series of spaced apart latching portions arranged to provide en- 105 gagement between said latch keeper and said latching bar in any adjusted position of the shelf on which said latch keeper is mounted.

2. A metal shelving, comprising spaced 110 uprights having spaced slots providing means for supporting a shelf at a variable elevation between said uprights, a shelf engaging portions of said slots, a door ar- 115 ranged to operate between said uprights and having hinge engaging portions spaced along a vertical edge thereof, said hinge en- 120 gaging portions registering with said spaced slots, a hinge secured in one of said hinge engaging portions and in the unoccupied portion of a registering shelf supporting slot, a latch keeper and door stop carried by said shelf, a shiftable latching bar carried by said door and having spaced catches thereon and arranged to engage said latch keeper in all mounted positions of said keeper corresponding with the possible mounted positions of the shelf.

3. A metal shelving, comprising uprights having spaced slots therein, a shelf adapted 130

- to removably engage registering slots to provide a vertically adjustable shelf supported between said uprights, a door having a plurality of hinge engaging portions spaced upon an edge, the spacing of which corresponds with the spacing of said slots, a hinge engaging one of said uprights and secured in an unoccupied portion of said shelf supporting slot, said hinge having a portion engaging a said hinge engaging door portion registering with said shelf supporting slot, a latch keeper secured to said shelf and disposed opposite the swing edge of said door, a slidable latching bar secured upon said door and having spaced latching portions corresponding with said spaced slots and arranged for registering engagement with said keeper to provide latching of the door at any vertically adjusted position of said shelf.
4. Metal shelving, comprising uprights having shelf supporting slots in their sides, shelves supported in said slots to provide an adjustable shelf tier, a door closure arranged to close against said shelf tier and hinges adjustably engaging said door closure and vacant portions of the slots in which said shelves are supported.
5. Metal shelving, comprising uprights having spaced slots arranged to support shelf members, shelf members engaging portions of said slots to provide a tier of adjustable shelves, a door having hinge supporting portions registering with the spaced slots of said uprights and hinges engaging unoccupied portions of said shelf
- supporting slots and said registering hinge supporting door portions.
6. Metal shelving, comprising uprights having spaced shelf supporting slots, shelves supported in said slots, a hinged door supported between said uprights, a latching bar carried by said door and having latching elements spaced thereon to correspond with the said slots in said uprights, and members carried by said shelves for engaging said latching elements for locking the door in closed position.
7. Metal shelving, comprising uprights having shelf supporting slots in their sides, said slots being adapted to adjustably support shelves at various heights, shelves supported in said slots, door hinged to said uprights, a latching bar carried by one of the doors, said bar having a plurality of spaced portions thereon corresponding with said spaced slots in the uprights and arranged to engage means on one of said shelves to lock the doors in closed relation.
8. In a metal shelving, uprights, a door of sheet metal and having an inwardly extending flange arranged adjacent said upright, a portion of said flange being slit from the remainder and rolled upon itself, a hinge member for connecting said door to said upright, said hinge member having a rolled portion entering into hinge relation with the rolled portion of said flange, and said hinge member engaging above and below said rolled portion of the flange.

WALTER N. VANCE.
